UNITED STATES PATENT OFFICE.

HERMAN F. VON OHLEN, OF NEW YORK, N. Y., ASSIGNOR TO CROUCH & FITZGERALD, A CORPORATION OF NEW YORK.

WARDROBE-TRUNK.

No. 906,158.

Specification of Letters Patent.

Patented Dec. 8, 1908.

Application filed December 21, 1907. Serial No. 407,492.

To all whom it may concern:

Be it known that I, HERMAN F. VON OHLEN, a citizen of the United States, and a resident of the borough of Manhattan, 5 county, city, and State of New York, have invented certain new and useful Improvements in Wardrobe-Trunks, of which the following is a specification.

This invention relates to garment receptacles which may preferably be in the form 10 of wardrobe trunks.

An object of the invention is to provide for the non-injurious and compact packing of garments in a receptacle and such packing 15 that these garments may be rendered readily accessible and exposed to view by means of certain mechanism combined with the receptacle. This mechanism may be in the form of one or more movable hanger rods pivotally secured to a trunk portion and capable 20 of being swung out into outward position when the garment receptacle is open.

In the preferred embodiment of the invention, the garment receptacle is in the form of 25 a salesman's trunk constructed so as to comprise a rectangular body portion and a cover portion approximating in size with that of the body portion, said portions being hinged together along corresponding vertical edges so 30 that, when they are closed together, they form a box-like receptacle. A hanger rack is pivotally secured near one vertical edge to one of said portions so as to occupy a vertical transverse mid-position in the receptacle when it 35 is closed and so as to be capable of being swung out upon a vertical axis located adjacent to the hinges for the cover portion so that, when it is swung out, it may occupy a vertical plane approximately mid way between the body portion and the cover portion. 40 One or more horizontal hanger rods are provided for this hanger rack and are each capable of supporting a series of garment hangers in a manner well known in the art.

Various combinations of coöperating elements for the hanger rods and rack etc. are contemplated in this invention. It is advantageous to provide locking means for the 45 hanger hooks to lock the same upon the hanger rods when these are retracted. In a preferred embodiment, a top hanger rod is provided and locking means secured to the garment receptacle coöperates therewith.

One or more lower hanger rods may also be 55 provided and locking means secured to the hanger rack may coöperate therewith. Means other than the pivotal support for the hanger rack may be provided for supporting said rack when in its outward position. In a preferred embodiment this means may comprise an extension member for engagement with the floor upon which the receptacle rests. Followers or compressor frames may be secured to the hanger rods to assist in packing 60 the garments suspended therefrom. Suitable stops may also be provided to hold the hanger rods in mid position when the receptacle is closed.

For the purposes of illustration, a preferred embodiment of the invention is shown 70 in the accompanying drawings, which form part of this application, in which like numerals designate corresponding parts, and in which,—

Figure 1 is a front elevation of a salesman's trunk showing the interior mechanism in outward position; Fig. 2 is a horizontal section through line 2—2 of Fig. 1; Fig. 3 is a front elevation with parts broken away 80 showing the interior mechanism in inward position; Fig. 4 is an enlarged detail view showing the extension member for supporting the hanger rack when in both outward and inward positions; Fig. 5 is a horizontal 85 section through line 5—5 of Fig. 4; Fig. 6 is an enlarged section through line 6—6 of Fig. 3; Fig. 7 is a horizontal section corresponding to Fig. 2 but with the hangers removed and showing a modified construction for supporting the hanger rack when in outward position; and Fig. 8 is a detail view showing the lower inner corner of the rack and associated parts as illustrated in Fig. 7.

Referring now more in detail to the drawings,—1 indicates a garment receptacle in the form of a wardrobe trunk and comprises a body portion 2 and a cover portion 3. This receptacle is shown in the drawings in its normal position for the accessibility of the garments to be contained therein. The cover portion 3 is hinged to the body portion 2 along the corresponding vertical edges 4 and 5 by means of any suitable hinges such as 6, 7 and 8.

It should be noted that the cover portion approximates in size that of the body portion 2 and, when closed together, completes

75

105

a box-like receptacle which may be held together in closed position by any suitable means such as a hasp 9.

A hanger rack 10 is pivotally secured to the body portion 1 so as to occupy a vertical mid transverse position as indicated by dotted lines in Fig. 2 when the receptacle is closed and so as to be capable of swinging out like a door into the outward position shown in full lines in Figs. 2 and 7 when the trunk is open. This hanger rack preferably comprises one or more horizontal hanger rods such as the top rod 11 and the lower rod 12. These rods may be secured to two side bars such as the pivot bar 13 and the swinging bar 14.

15 indicates an additional cross rod secured to the side bars. In the present construction, the hanger rods 11 and 12 are capable of swinging from inward to outward position by reason of the pivoting of the bar 13 in the bearings 16, 17 and 18 which are secured to the body portion 2 so that the axis about which the hanger rods 11 and 12 swing is vertical and adjacent to that of the hinges 6, 7 and 8.

The hanger rods 11 and 12 are adapted each to sustain a series of garment hangers such as 19 and 20 respectively, the hooks 21 and 22 of which respectively engage the hanger rods in a well known manner so that garments supported by these hangers and the hangers extend transversely to the hanger rods themselves and depend in the open spaces of the hanger rack provided therefor and as illustrated. There may also be hooked upon each hanger rod a follower member such as 23 and 24 which is shown in the form of a suitable compressor frame and which may be pressed against the suspended garments by means of the buckle straps 25 and 26. The ends of the buckle strap 26 may be anchored, one to a ring 27 secured to the underside of the hanger rod 12, 45 and one to a ring 28 secured to the crossbar 15. The buckle strap 25 may have its ends secured in a similar manner, one to a ring 29 secured to the hanger rod 11, and one to a ring 30 secured to the rod 31. This rod 31 is illustrated as being adjustably secured to the bars 13 and 14 of the hanger rack by thumb screws 32 and 33. In its present embodiment it may be moved up or down on the hanger rack and set in position by means of 55 the screws 32 and 33. When it is in the position illustrated in the drawings, the downward projection 34 engages the hooks 22 of the lower series of hangers and locks them upon the hanger rod 12.

60 A downward projecting member 35 is secured to the body of the trunk 2 and like the rod 31 with its projection 34, serves as means for locking hangers upon a hanger rod, in this instance, the hanger rod 11.

65 Figs. 3 and 4 indicate the hanger rack in its

inward position in which the swinging rod 14 abuts against suitable stops 36 and 37 to limit its inward movement. When the cover portion 3 is closed against the body portion, similar stops 38 and 39 on the cover portion close against the opposite side of the swinging rod 14 and serve to hold the hanger rack and consequently the hanger rods in their mid position. The stop 36 may be provided with a wedge-like face under which the upper end of the swinging rod 14 engages to secure said swinging rod 14 firmly against endwise movement during transportation of the garment receptacle 1. The lower extremity of the rod 14 or an extension thereof should likewise engage with the bottom wall 40 of the receptacle to prevent endwise movement of the rod 14 in that direction.

It is preferred that suitable means separate from the pivot connection of the hanger rods 11 and 12 and cross rod 15 may be provided for supporting the hanger rods when they are in outward position, viz., that indicated in Figs. 2 and 7. A preferred embodiment of this means is shown in detail in Figs. 90 4 and 5. The swinging rod 14 which, like all the other rods, may preferably be made of piping, is provided with a telescoping extension member 41 which may be controlled by the pin 42 completing a bayonet joint with 95 the slot 43 formed in the bar 14. Figs. 3 and 4 show this extension member in its upward position so that a caster or roller 44 provided at its foot may engage with the bottom wall 40 of the body portion 2 and support the 100 hanger rack when in inward position. When the hanger rack is swung outwardly, the extension member 41 may be depressed by means of the pin 42 and locked in its depressed position so that the caster 44 engages 105 the floor 45 upon which the trunk rests and to support the hanger rack 10.

A modified means for supporting the hanger rack and separate from the pivotal connection of the hanger rack with the trunk 110 is shown in Figs. 7 and 8. A caster or roller 46 is secured to the crossbar 15 so as to have rolling engagement with the arc-shaped slotted track 47 secured to the bottom walls of the trunk portions 2 and 3 by means of the 115 headed pins 48 and 49. Fig. 7 illustrates the track 47 in its relative position when the trunk is open. When the trunk is closed, the pins 48 and 49 slide towards one another in the slots 50 and 51.

The hanger rack may be set up in any manner well known in the art as by the couplings indicated. It should also be noted that although piping provides suitable material for forming the hanger rack, other material may 125 advantageously be employed. It is also contemplated that an extension member 41 might be provided which did not of necessity telescope with the swinging bar 14.

It is to be noted that when the garment re- 130

ceptacle or trunk 1 is open and the hanger rack is swung out into outward position that any one or more of the garment hangers such as 19 and 20 may be removed and replaced at 5 will or be transferred from one place to another while all the garments supported by a hanger rod are exposed to view. This feature is of particular advantage to salesmen in showing a line of goods. A trunk construction such as that illustrated and described is suitable for transporting and displaying waists and although but two hanger rods have been illustrated, it is to be understood that these are merely for the purpose 10 of illustration and that the number may be varied as desired.

Many of the features of this invention are capable of other embodiments, within the scope of the following claims, than that illustrated and described and it is also to be understood that various combinations of the elements illustrated are contemplated.

What is claimed and what is desired to be secured by United States Letters Patent 25 is:—

1. In garment receptacles, an open faced body portion; a rigid rectangular hanger frame having one or more horizontal hanger rods extending from side to side of said frame 30 arranged and designed to support suspended transverse coat hangers; fixed pivotal means securing said hanger frame to the body portion so as to swing on a vertical axis; and coat hangers suspended from and sliding on 35 said horizontal rods.

2. In garment receptacles, an open faced body portion; a rigid rectangular hanger frame having one or more horizontal hanger rods extending from side to side of said frame 40 arranged and designed to support suspended transverse coat hangers; fixed pivotal means securing said hanger frame to the body portion so as to swing on a vertical axis; coat hangers and a follower suspended from and 45 sliding on said horizontal rods; and a hinged cover portion having its axis on the same side of the body portion as the hanger frame.

3. In a wardrobe trunk, a body portion; a cover portion; hinges securing said portions 50 together along corresponding vertical edges, said portions forming a box-like garment receptacle when closed together; a hanger rack; fixed pivotal means securing said rack to a trunk portion so as to swing out on a vertical 55 axis adjacent to said hinges when the trunk is open and to occupy a mid position when the trunk is closed, said hanger rack comprising two vertical side bars and a top horizontal hanger rod secured thereto and a 60 lower hanger rod also secured thereto; a series of hangers for each hanger rod and extending transversely to the hanger rack; means secured to a trunk portion for locking 65 the top hangers upon the top hanger rod; and an adjustable means carried by said rack

for locking the hangers upon a lower hanger rod.

4. In a wardrobe trunk, a body portion; a cover portion hinged to the body portion along a vertical edge; a hanger rack; fixed 70 pivotal means for securing said hanger rack to said body portion to swing outwardly on an axis parallel to said vertical edge; and one or more hanger rods extending from side to side of said hanger rack for supporting 75 transverse hangers; coat hangers suspended from and sliding on said horizontal rods said hanger rack comprising a vertical pivot bar and a horizontally spaced vertical swinging bar to which said hanger rods are secured. 80

5. In a wardrobe trunk, a body portion; a cover portion hinged to the body portion along a vertical edge; a hanger rack; pivotal means for securing said hanger rack to said body portion to swing outwardly on an 85 axis parallel to said vertical edge; and one or more hanger rods on said hanger rack for supporting hangers; and means separate from said pivotal means for supporting said rack when in outward position. 90

6. In a wardrobe trunk, a body portion; a cover portion hinged to the body portion along a vertical edge; a hanger rack; pivotal means for securing said hanger rack to said body portion to swing outwardly on an 95 axis parallel to said vertical edge; and one or more hanger rods on said hanger rack for supporting hangers; said hanger rack comprising a vertical pivot bar and a horizontally spaced vertical swinging bar to which said 100 hanger rods are secured; and an extension member for said swinging bar to engage the floor and support said rack when in outward position.

7. In a wardrobe trunk, a body portion; a 105 cover portion hinged to the body portion along a vertical edge; a hanger rack; fixed pivotal means for securing said hanger rack to said body portion to swing outwardly on an axis parallel to said vertical edge; and one 110 or more hanger rods extending from side to side of said hanger rack for supporting transverse hangers; a sliding follower member suspended from a hanger rod; and means for binding said follower member against the 115 garments suspended.

8. In a wardrobe trunk, a body portion; a cover portion hinged to the body portion along a vertical edge; a hanger rack; pivotal means for securing said hanger rack to said 120 body portion to swing outwardly on an axis parallel to said vertical edge; and one or more hanger rods on said hanger rack for supporting hangers; said hanger rack comprising a vertical pivot bar and a horizontally 125 spaced vertical swinging bar to which said hanger rods are secured; and an extension member for said swinging bar and provided with a caster to engage the floor and support said rack when in outward position. 130

9. In a wardrobe trunk, a body portion; a cover portion hinged to the body portion along a vertical edge; a hanger rack; pivotal means for securing said hanger rack to said body portion to swing outwardly on an axis parallel to said vertical edge; and one or more hanger rods on said hanger rack for supporting hangers; said hanger rack comprising a vertical pivot bar and a horizontally spaced vertical swinging bar to which said hanger rods are secured; and an adjustable extension member telescoping with said swinging bar to engage the floor and support said rack when in outward position.
10. 10. In a wardrobe trunk, a body portion; a cover portion hinged to the body portion along a vertical edge; a hanger rack; pivotal means for securing said hanger rack to said

body portion to swing outwardly on an axis parallel to said vertical edge; and one or 20 more hanger rods on said hanger rack for supporting hangers; said hanger rack comprising a vertical pivot bar and a horizontally spaced vertical swinging bar to which said hanger rods are secured; and an ad- 25 justable extension member telescoping with said swinging bar and provided with a caster to engage the floor and support said rack when in outward position.

In testimony whereof, I have signed my 30 name to this specification, in the presence of two subscribing witnesses.

HERMAN F. VON OHLEN.
